UNITED STATES PATENT OFFICE.

GEORGE W. BROWN, OF MARIETTA, OHIO.

CUFF BUTTON.

Application filed September 25, 1925. Serial No. 58,638.

This invention contemplates the provision of a collar or cuff button of novel construction, wherein the head of said button is capable of being rotated with relation to the base, cooperating means forming part of the base and head respectively for holding the said head fixed with relation to the base in any given position, and requiring the application of positive force to turn the head 10 to another position.

The nature and advantages of the invention will be better understood when the following detailed description is read in connection with the accompanying drawings, 15 the invention residing in the construction, combination and arrangement of parts as claimed.

In the drawing forming part of this application, like numerals of reference indicate similar parts in the several views and 20 wherein:

Figure 1 is a view in elevation of the button constructed in accordance with the present invention.

25 Figure 2 is a view taken at a right angle to Figure 1.

Figure 3 is a top plan view.

Figure 4 is a sectional view taken on line 4—4 of Figure 1.

30 Figure 5 is a sectional view taken on line 5—5 of Figure 2.

Figure 6 is a view showing how the head of the button may be turned with relation to the base.

35 Figure 7 is a view taken at a right angle to Figure 2.

Figure 8 is a sectional view taken on line 8—8 of Figure 4.

40 Figure 9 is a sectional view taken on line 9—9 of Figure 6.

Referring to the drawing in detail 10 indicates the base of the button while 11 represents the head thereof, the base being provided with a central opening 12 for a purpose to be presently described. The shank of the button carried by the base 10 is preferably made up of two parts 13, each having a reduced extremity 14, which corresponding extremities are arranged side by side and positioned within the opening 12 of the base as clearly illustrated in Figure 5. The purpose of making the shank of the button in two parts is to allow such parts to be slightly separated in the manner shown in Figure 6 when it is desired to turn or rotate the head 11 of the button with relation to the base 10,

to facilitate passing of the button through the button holes in the garment with which it is used. Each part of the shank is provided with a V-shaped groove 15 which extends throughout the major portion of the length thereof, and these grooves 15 unitedly define a socket which is square in cross section as shown in Figure 8 to accommodate the squared extension 16 projecting 65 from the head 11 of the button as shown. This extension is formed at its lower end with an enlargement 17 received by aligned openings 18 formed in the respective parts of the shank, the enlargement 17 prohibiting 70 the head from being casually separated from the shank of the button as will be readily understood. This construction allows the head 11 to be rotated with relation to the base 10 so that the head may occupy one 75 position to facilitate the passing of the button through the button hole of the garment with which it is used, and subsequently turned to occupy another position with relation to the base for holding the button 80 against accidental displacement therefrom.

It is of course to be understood that the parts 13—13 of the shank are susceptible of being slightly flexed incident to the rotation of the head 11 as clearly shown in Figure 6, 85 at which time the parts 13—13 are slightly tensioned so as to snap back into place when the head 11 has been given the desired position with relation to the base 10. It is the squared extension 16 that separates these 90 parts 13 of the shank until the corners of said extension are arranged to be received by the grooves 15 of the shank above described. When the head of the button is in either of the positions shown in Figure 8, the parts 13—13 of the shank occupy their 95 normal position and hold the head against casual movement, so that accidental displacement of the button from the garment is prohibited.

While it is believed that from the foregoing description the nature and advantages of the invention will be readily understood, I desire to have it known that I do not limit myself to what is herein shown and described, and that such changes may be resorted to when desired, as fall within the scope of what is claimed.

Having thus described the invention, I claim:

A button of the character described comprising a base, a shank associated therewith

and including relatively movable parts, each part having a V-shaped groove longitudinally thereof, said grooves unitedly defining a socket square in cross section and at the opposite sides of the shank, and having openings beneath said socket, a head including a squared extension adapted to be received by said socket whereby said head is capable of being rotated with relation to

the base, said extension cooperating with 10 said grooves for holding said head fixed with relation to the base in a given position, and an enlargement carried by the lower end of said extension and operating in said opening, and holding said head against casual separation from the shank. 15

In testimony whereof I affix my signature.
GEORGE W. BROWN.
